MACHINE FOR THE TREATMENT OF
LENSSES

Jacques Bolsey, New York, N. Y.

Application January 29, 1943, Serial No. 473,931

8 Claims. (CL 51—108)

My present invention relates to machines for simultaneously subjecting a plurality of lenses to various treatments, more particularly to machines for simultaneously subjecting a plurality of lenses to centering, grinding, and polishing.

It is an object of my present invention to provide a machine adapted to support a plurality of lenses or lens blanks during treatment of the same.

It is another object of my invention to provide a machine of the above type which needs substantially no skill and long experience for its operation.

Still another object of my present invention consists in a machine adapted to center the lenses or lens blanks automatically on their supports before treatment of the same by grinding and polishing tools forming part of this machine.

A further object of my invention consists in new lens supporting devices combined with my new machine.

Still a further object of the invention consists in centering devices enabling substantially automatic centering of the lenses or lens blanks on their individual supports.

With the above objects in view, my present invention mainly consists in a machine for the above explained purposes comprising a common horizontal support for a plurality of lenses arranged rotatably about a common vertical axis of rotation and individual supports, one for each of the lenses, arranged on this common horizontal support equidistant from the vertical axis of the same. Each of these individual supports is preferably also arranged rotatably about an individual vertical axis of rotation.

Of course, the machine also comprises means for rotating the common support about the common vertical axis of rotation and means for rotating each of the individual lens supports about its individual axis of rotation. In this manner, all lenses are supported in horizontal position rotating about vertical axes of rotation, thereby enabling placing of the lenses on their supports and centering of the same on these supports without being secured to them.

My new machine preferably comprises a plurality of individual supports arranged equidistant from each other and from the common vertical axis of rotation of the common support; in this case, the means for rotating the common support are constructed in such a manner as to rotate this support intermittently step by step, moving each of the individual lens supports by one of these step by step movements into that position

in which the next following lens support was before that respective movement.

The rotation of the individual lens supports about their individual axes of rotation is preferably uninterrupted and continuous and serves for obtaining the necessary relative movement between the grinding and polishing tools and the lenses; this rotation furthermore enables centering of each of these lenses on its individual support in the way described below more in detail.

I have found it advantageous to obtain this step by step rotation of the common support by means of a Geneva cross mechanism or rotating means acting in the same or similar way. By such a mechanism, I obtain step by step movements of which each consists of three periods, namely one period of quick turning, one period of slow turning, and one period of rest. Preferably, during the period of quick turning, each of the individual supports moves substantially the entire distance from one position of rest to the next, and during the period of slow turning it moves only a short distance before reaching this next position of rest; in this next position of rest, then, it remains for a considerable period of time which might be equal to about the length of the quick and the slow turning period together.

This way of moving the support has considerable advantages, as during the period of quick turning the supported lenses are in no contact with any of the tools of the machine but are only carried from one tool to the next while during the period of slow turning they are coming into contact with the tools and during the periods of rest they are treated by the same. It is essential to stress that these intermittent periods of turning and rest relate only to the rotation of the common support about the common axis of rotation and not to the rotation of the individual supports about their respective axes, which latter movement is continuous and uninterrupted during the entire operation of the new machine.

As explained above, the general construction of my new machine supporting the lenses in horizontal position has substantial advantages in that no separate fastening means are necessary during placing and centering of the lenses and that the same are prevented from detachment from their supports during these operations solely by force of gravity. Of course, during treatment of the lenses by grinding, polishing, or other tools, the force of gravity is insufficient and other fastening means have to be provided. I have found that best results can be obtained in a simple way

by using vacuum for securing the lenses or lens blanks to their supports, as fastening devices working with vacuum are extremely simple in construction and easy to operate. Furthermore, such devices enable in a simple way reduction of adherence of the lenses to their supports whenever such reduction should be required for purposes of centering or like operations.

For centering the lenses, I preferably use photo-electric lens centering devices of the type described in my co-pending United States patent application, Ser. No. 471,325, filed on January 5, 1943. It is advantageous to use several such centering devices associated with consecutive positions of rest of the individual lens supports, enabling subdivision of the centering operation into rough and fine centering of the lenses on their supports. As such centering devices operate by themselves and in view of the fact that fastening means working with vacuum might also be operated by rotation of the common support, my new machine is adapted to work entirely automatically; this means that the lenses only have to be placed on their individual supports in uncentered position and will then automatically be centered by the photo-electric centering devices described below in detail, automatically fastened to their supports by vacuum means, moved into such position as to contact consecutively the grinding and polishing tools while rotated and, after treatment by these tools, released from their supports also automatically. Thus, no skill and long experience is necessary for operating my new machine; furthermore, it is evident that treatment of lenses in the way proposed above is much faster than obtainable with machines of known type.

The novel features which I consider characteristic for my invention are set forth in particular in the appended claims. The invention itself, however, both as to its construction and its method of operation, together with additional objects and advantages thereof, will be best understood from the following description of specific embodiments, when read in connection with the accompanying drawings, in which:

Figure 1 is a side view of the entire machine;

Figure 2 is an elevational cross section through the upper part of the machine shown in Figure 1;

Figure 3 is a front view of the machine shown in Figure 1;

Figure 4 is a top view of the driving mechanism with the upper part of the machine removed;

Figure 5 is a top view of the machine showing the individual lens supports;

Figure 6 is a view similar to the view shown in Figure 5;

Figure 7 is a perspective view of the common and individual lens supports;

Figure 8 is an elevational section of one of the individual lens supports;

Figure 9 shows another embodiment of the mechanism rotating the common support in elevational section; and

Figure 10 shows a detail of the photo-electric lens centering means used in combination with my new machine.

As explained above and shown in the drawings, particularly in Figures 1, 5, 6, and 7, my new machine comprises a common horizontal support 3 arranged rotatably about a vertical shaft 17, and individual horizontal supports 4, 5, 6, 7, 8, 9, 34, and 35, arranged on the common support 3 equidistant from shaft 17 and from each other. As shown in Figure 1, the common support 3 is

arranged on top of the rotating mechanism 2 which latter is supported by base 1. The individual supports listed above are rotatable about their individual axes which, as shown in the drawings, are also vertical, thereby enabling support of the lenses in horizontal position by these individual supports.

In the drawings, two different mechanisms for rotating the common support 3 and the individual supports are shown: the embodiment shown in Figures 7 and 9 comprises the stationary shaft 17 supported by a base, two gears 51 and 52, non-rotatably secured to this shaft 17, and pinions 19, 20 secured to the lower ends of the lens supporting hollow spindles 4, 5, 6, 7, 8, 9, 34, and 35. These spindles are rotatably carried by the common support 3 which latter is supported rotatably about shaft 17 by means of ball bearings 53 and 54. Motor 54' is secured to support 3 in the way shown in Figure 9; this motor is connected with gear 52 by means of worm gear 55, shaft 56, and pinion 51. As gear 52 is firmly secured to the stationary shaft 17 and is unable to rotate, operation of the motor will cause rotation about shaft 17 of the motor and of the common support 3 to which this motor is secured. In view of the fact that the stationary gear 51 is in mesh with the rotatable pinions 19, 20, it is evident that when the common support 3 is rotated, the pinions 19, 20, are rotated about their individual axes and thereby rotate the lens supporting hollow spindles to which they are secured. Thus, operation of motor 54' causes not only rotation of the common support 3 about shaft 17 but also rotation of each of the lens supporting individual spindles about its individual axis of rotation.

The mechanism rotating the common support shown in Figures 2 and 4 differs from the one described above mainly by the fact that motor 24 is stationarily supported and not rotating with the common support 3. This stationary motor 24 is connected by worm 25 and worm gear 26 with the rotatable driving shaft 23. By means of pulleys 22 and 28 and belt 21, this shaft drives shaft 17 which in this case is rotatably supported and not stationary as in the embodiment described above. Shaft 17 is connected to the individual lens supporting spindles by means of gear 18 and pinions 19, 20, and rotates each of those spindles about its individual axis of rotation.

While the shaft 17 turns continuously and thus the lens supporting spindles are rotated without interruption, the mechanism for rotating the common support 3 is constructed in such a manner as to cause intermittent step by step turning of this support. For this purpose the driving shaft 23 is connected by means of pulleys 27, 29 and belt 28 to shaft 30, rotating the latter with uniform speed. Shaft 30 carries the cylindrical member 31, to which pin 32 is secured. This pin co-operates, as shown in Figure 4, with the Geneva cross 33 which latter is firmly connected to the common support 3 by means of the hollow sleeve member 16.

It is evident to everybody skilled in this art and needs no further explanation that in this way the continuous uniform rotating movement of shaft 30 is transformed into a step by step intermittent movement of the Geneva cross 33 and the common support 3 driven by the same. It is also evident that a mechanism of this type causes varying speed of rotation between consecutive positions of rest of support 3, namely first a quick and then a slow turning of the support. The Geneva cross might be shaped in such a manner

that during the quick turning the support 3 moves substantially the entire way from one position of rest to the next while during the slow turning it moves only a short distance before reaching the next position of rest. Thus, I have found it advantageous to construct this driving mechanism in such a way that the quick turning period is somewhat shorter than the slow turning period and each period of rest lasts as long as both the quick and slow turning periods together. Furthermore, the distance covered during the quick period should be about four to six times as great as that covered during the consecutive slow movement of support 3.

Having thus described in detail my new lens supporting means and the mechanism for rotating the same, I will now proceed to describe the means for fastening the lenses to their supports, the lens centering devices and other lens treating means associated with my new machine.

As shown in the drawings, particularly in Figures 2, 8, and 9, each of the individual lens supports consists of a hollow spindle 60 connected with gear 68 and arranged rotatably on the common support 3. Each of these spindles 60 is provided with a nozzle 61, the upper rim 62 of which serves for supporting the lens 63 as shown in Figure 8. The nozzle 61 may be exchangeable in order to use nozzles of various size for variously shaped lenses.

I have found it advantageous to combine with the lens supports lens centering devices of the type described in my co-pending applications, Ser. No. 471,325, filed January 5, 1943. Such a lens centering device consists of a source of light, e. g. a lamp 66, a lens 68 in front of this lamp, a diaphragm 69, and a set of photo-electric cells 67 and 68 arranged on the stationary support 12 as shown in Figure 1. This latter support is connected to the stationary base 1 by member 14 and does not rotate together with the common support 3. Connected with the photo-electric cells 68 are electro-magnetic means, not shown in the drawings, for operating the adjusting lever 69 in such a manner as to correct the position of lens 63 whenever the light beam emitted by lens 64 and passing through lens 63 is deflected from its correct position, co-inciding with the axis of rotation of spindle 60. It is possible to provide several centering devices of this type, for instance one for rough and one for fine centering, and to associate them with two consecutive positions of rest, as for instance those positions in which the lens supports 1 and 8 are in Figure 5.

For securing the lenses to their individual supports, vacuum means are used. As shown in Figure 9, these vacuum means consist of a pump 70 creating a vacuum within the common support 3 and thereby holding the lenses 63 firmly in contact with the rims 62 of nozzles 61. As mentioned above, it is necessary to regulate this vacuum, i. e. to decrease the air suction in some of the nozzles in order to enable centering of the lenses. For this purpose, I provide two valves 71 and 72 co-operating with each other in such a manner that the space within those nozzles which are co-operating with lens centering devices is disconnected from the inner space within support 3. This can easily be attained by automatically opening valve 72 and closing valve 71 before the nozzles reach the lens centering devices and reversing the position of the valves when the lenses are centered and the nozzles are moving away from these devices. In order to avoid undesired sliding of the lenses during centering, additional

supporting means 73 and 74 might be provided.

As shown in the drawings, particularly in Figures 1, 5, 6, and 7, grinding and polishing wheels 8a, 31, and 32, are provided near some points of the path of the lenses, preferably near such points at which the lenses are in a position of rest. In view of the fact that the lenses are rotating about their individual axes also during rest periods, grinding and polishing of the lens edges is carried out during these periods.

It will be understood that each of the elements described above, or two or more together, may also find a useful application in other types of lens treating apparatus differing from the types described above.

While I have illustrated and described the invention as embodied in lens centering and grinding machines, I do not intend to be limited to the details above, since various modifications and structural changes may be made without departing in any way from the spirit of my invention.

Without further analysis, the foregoing will so fully reveal the gist of my invention that others can, by applying current knowledge, readily adapt it for various applications without omitting features that, from the standpoint of prior art, fairly constitute essential characteristics of the generic or specific aspects of this invention and therefore such adaptations should and are intended to be comprehended within the meaning and range of equivalence of the following claims.

What I claim as new and desire to secure by Letters Patent is:

1. Machine for simultaneously subjecting a plurality of lenses to various treatments comprising a common horizontal support for said lenses arranged rotatably about a common vertical axis of rotation, individual horizontal supports one for each of said lenses arranged on said common horizontal support equidistant from each other and from said common vertical axis of rotation, each of said individual supports being arranged rotatably about an individual vertical axis of rotation, means for rotating said common support step by step intermittently about said common vertical axis of rotation in such a manner as to move each of said individual lens supports into that position in which the next preceding lens support was before that respective step by step rotating movement, means for continuously rotating each of said individual lens supports about its individual vertical axis of rotation during said step by step intermittent rotation of the common support about its common vertical axis of rotation, each of said individual supports having an upper horizontal rim for supporting a lens freely slidable in horizontal position, and stationary optical centering means adapted to center the optical center of the lenses with respect to the individual supports while they are lying freely slidably on said upper horizontal lens supporting rims of said supports, said optical centering means being arranged along the path of the lenses carried by said individual lens supports at some of those points of this path at which said individual lens supports are in position of rest, not rotating about said common vertical axis of rotation of said common support.

2. Mach'ne for simultaneously subjecting a plurality of lenses to various treatments comprising a common horizontal support for said lenses arranged rotatably about a common vertical axis of rotation, individual horizontal supports one for each of said lenses arranged on said common horizontal support equidistant from each other

and from said common vertical axis of rotation, each of said individual supports being arranged rotatably about an individual vertical axis of rotation, means for rotating said common support step by step intermittently about said common vertical axis of rotation in such a manner as to move each of said individual lens supports into that position in which the next preceding lens support was before that respective step by step rotating movement, means for continuously rotating each of said individual lens supports about its individual vertical axis of rotation during said step by step intermittent rotation of the common support about its common vertical axis of rotation, each of said individual supports comprising a nozzle having an upper horizontal rim for supporting a lens freely slidable in horizontal position and means for creating vacuum inside said nozzle adapted to cause firm adherence of a lens placed on said supporting nozzle rim to the same during the consecutive various treatments to which said lens is subjected during its combined rotation about the common vertical axis of rotation of said common support and about its individual vertical axis of rotation, stationary optical centering means adapted to center the optical center of the lenses with respect to the individual supports while they are lying in horizontal position freely slidably on said upper horizontal lens supporting rim of said supports, said optical centering means being arranged along the path of the lenses carried by said individual lens supports at some of those points of this path at which said individual lens supports are in position of rest, not rotating about said common vertical axis of rotation of said common support, means for reducing the vacuum in those nozzles which are at those points of the path of the lenses at which said lens centering means are arranged, and various stationary grinding and polishing means arranged at some other points of the path of said lenses carried by said individual supports in such a manner as to contact said lenses mainly while the individual lens supports carrying the same are in a position of rest not rotating about the common vertical axis of said common support but rotating only about their respective individual axes of rotation.

3. Machine for simultaneously subjecting a plurality of lenses to various treatments comprising a common horizontal support for said lenses arranged rotatably about a common vertical axis of rotation, individual horizontal supports one for each of said lenses arranged on said common horizontal support equidistant from each other and from said common vertical axis of rotation, each of said individual supports being arranged rotatably about an individual vertical axis of rotation, a Geneva cross type mechanism for rotating said common support step by step intermittently about said common vertical axis of rotation in such a manner as to move each of said individual lens supports into that position in which the next preceding lens support was before that respective step by step movement, means for continuously rotating each of said individual lens supports about its individual vertical axis of rotation during said step by step intermittent rotation of the common support about its common vertical axis of rotation, each of said individual supports comprising a nozzle having an upper horizontal rim for supporting a lens freely slidable in horizontal position and means for creating vacuum inside said nozzle adapted to cause firm adherence of a lens placed on said supporting nozzle rim to the same during

the consecutive various treatments to which said lens is subjected during its combined rotation about the common vertical axis of rotation of said common support and about its individual vertical axis of rotation, stationary optical centering means adapted to center the optical center of the lenses with respect to the individual supports while they are lying in horizontal position freely slidably on said upper horizontal lens supporting rim of said supports, said optical centering means being arranged along the path of the lenses carried by said individual lens supports at some of those points of this path at which said individual lens supports are in position of rest, not rotating about said common vertical axis of rotation of said common support, means for reducing the vacuum in those nozzles which are at those points of the path of the lenses at which said lens centering means are arranged, and various stationary grinding and polishing means arranged at some other points of the path of said lenses carried by said individual supports in such a manner as to contact said lenses mainly while the individual lens supports carrying the same are in a position of rest not rotating about the common vertical axis of said common support but rotating only about their respective individual axes of rotation.

4. Machine for simultaneously subjecting a plurality of lenses to various treatments, comprising a common movable horizontal lens support for said lenses, individual horizontal supports one for each of said lenses arranged on said common horizontal movable support equidistant from each other, each of said lens supports having an upper horizontal lens supporting part on which the supported lens is adapted to lie freely slidably in horizontal position, means for moving said common support step by step intermittently in such a manner as to move each of said individual lens supports into that position of rest in which the next preceding lens support was before that respective step by step movement, and lens centering means adapted to center said lenses after they have been placed upon said upper horizontal lens supporting parts of said horizontal supports in horizontal position freely slidably supported by the same, said centering means being arranged along the path of the lenses carried by said individual lens supports at least at one of those points of this path at which said individual lens supports are in position of rest.

5. Machine for simultaneously subjecting a plurality of lenses to various treatments comprising a common movable horizontal lens support for said lenses, individual horizontal supports one for each of said lenses arranged on said common horizontal movable support equidistant from each other, each of said lens supports having an upper horizontal lens supporting part on which the supported lens is adapted to lie freely slidably in horizontal position, means for moving said common support step by step intermittently in such a manner as to move each of said individual lens supports into that position of rest in which the next preceding lens support was before that respective step by step movement, and stationary optical lens centering means adapted to center the optical center of the lenses with respect to the lens supports on which they are freely slidably in horizontal position lying after they have been placed upon said upper horizontal lens supporting parts of said horizontal lens support freely slidably supported by the same in hori-

zontal position, said stationary optical lens centering means being arranged along the path of the lenses carried by said individual lens supports at some of those points of this path at which said individual lens supports are in position of rest.

6. Machine for simultaneously subjecting a plurality of lenses to various treatments comprising a common horizontal support for said lenses arranged rotatably about a common vertical axis of rotation, individual horizontal lens supports one for each of said lenses arranged on said common horizontal support equidistant from said common vertical axis of rotation, each of said individual supports being arranged rotatably about an individual vertical axis of rotation and having an upper horizontal lens supporting part on which the supported lens is adapted to lie freely slidably in horizontal position, means for rotating said common support step by step intermittently about said common vertical axis of rotation in such a manner as to move each of said individual lens supports into that position of rest in which the next preceding lens support was before that respective step by step rotating movement, means for rotating each of said individual lens supports about its individual vertical axis of rotation, and lens centering means adapted to center said lenses after they have been placed upon said upper horizontal lens supporting parts of said horizontal supports in horizontal position freely slidably supported by the same, said centering means being arranged along the path of the lenses carried by said individual lens supports at least at one of those points of this path at which said individual lens supports are in position of rest, not rotating about said common vertical axis of rotation of said common support.

7. Machine for simultaneously subjecting a plurality of lenses to various treatments, comprising a common movable horizontal lens support for said lenses, individual horizontal supports one for each of said lenses arranged on said common horizontal movable support equidistant from each other, each of said individual supports being arranged rotatably about an individual vertical axis of rotation and having an upper horizontal lens supporting part on which a lens is adapted to lie freely slidably in horizontal position, means for rotating each of said individual supports about its individual vertical axis of rotation, means for moving said common support step by step intermittently in such a manner as to move each of said individual lens supports into that position of rest in which the next preceding lens support was before that respective step by step movement, means for removing the finished lenses and means for placing lenses to be treated on said upper horizontal lens supporting parts of said horizontal lens supports in horizontal position freely slidably supported by the same, said means being arranged along the path of the lenses carried by said individual lens supports at least at one of those points of this path at which said individual lens supports are in position of rest and lens centering means adapted to center said lenses after they have been placed by said placing means upon said upper horizontal lens supporting parts of said individual horizontal lens supports freely slidably supported by the same in horizontal position, said centering means being arranged along the path of the lenses carried by said individual lens supports at least at one of those points of this path at which said individual lens supports are in position of rest not moving together with said common support but only rotating about their individual axes of rotation.

of the lenses carried by said individual lens supports at least at one of those points of this path at which said individual lens supports are in a position of rest and stationary optical lens centering means adapted to center the optical center of the lenses with respect to said horizontal lens supports after the same have been placed by said placing means upon said upper horizontal lens supporting parts of said individual horizontal lens supports freely slidably supported by the same in horizontal position, said centering means being arranged along the path of the lenses carried by said individual lens supports at least at one of those points of this path at which said individual lens supports are in position of rest, not moving together with said common movable horizontal support but only rotating about their individual vertical axes of rotation.

8. Machine for simultaneously subjecting a plurality of lenses to various treatments, comprising a common movable horizontal lens support for said lenses, individual horizontal supports one for each of said lenses arranged on said common horizontal movable support equidistant from each other, each of said individual supports being arranged rotatably about an individual vertical axis of rotation and having an upper horizontal lens supporting part on which a lens is adapted to lie freely slidably in horizontal position, means for moving said common support step by step intermittently in such a manner as to move each of said individual lens supports into that position of rest in which the next preceding lens support was before that respective step by step movement, means for continuously rotating each of said individual lens supports about its individual vertical axis of rotation during said step by step intermittent movement of said common support, means for removing the finished lenses and means for placing lenses to be treated on said upper horizontal lens supporting parts of said horizontal lens supports in horizontal position freely slidably supported by the same, said means being arranged along the path of the lenses carried by said individual lens supports at least at one of those points of this path at which said individual lens supports are in a position of rest and lens centering means adapted to center said lenses after they have been placed by said placing means upon said upper horizontal lens supporting parts of said individual horizontal lens supports freely slidably supported by the same in horizontal position, said centering means being arranged along the path of the lenses carried by said individual lens supports at least at one of those points of this path at which said individual lens supports are in position of rest not moving together with said common support but only rotating about their individual axes of rotation.

JACQUES BOLSEY.
